MEANS OF TEACHING PIANO PLAYING

Filed June 5, 1919

4 Sheets-Sheet 1

STOP - End of exercise No. 2.
Repeat No. 1 and No. 2, until
played same as player
at Tempo 20.

$C \rightarrow$ 5 Two octaves
above middle C.
C 4
B 3
A 2
G 1
F 3
E 2
D 1 One octave above
middle C.

$C \rightarrow$ Middle G - Exercise No. 2.
Right hand begin with
finger 1.

STOP - End of exercise No. 1.
 $C \rightarrow$ 10 First C below middle C.
C 2
B 1
A 0
G 1
F 2
E 3
D 4
C 5
B 6
A 7
G 8
F 9
E 10
D 11
C 12

Left hand begin with finger 1. Exercise No. 1.
Base clef, second C below middle C.

This illustrates left and right hands with fingers properly marked.

Fig. 1.

Thirty second notes	18	4	Thirty two thirty second notes equal one whole note. Eight notes to each count.
Sixteenth notes	17	4	Sixteen sixteenth notes equal one whole note. Four notes to each count.
Eight notes	16	4	Eight eighth notes equal one whole note. Two notes to each count.
Quarter notes	15	4	Four quarter notes equal one whole note. One note to each count.
Half notes	14	4	Two half notes equal one whole note. Two counts to each note.
Whole notes	13	4	Whole note Four counts to each measure.
Notes	12	4	One measure.
Rests.	11	4	
Dotted Notes-A dot placed after a note increases its length by one half. Ex: a whole note (o) is equal in length to two half notes (dd) but a dotted whole note (o.) is equal in length to three half notes (ddd) So a half note is equal to two quarter notes (dd); but a dotted half note (d.) is equal to three quarter notes (ddd). When two dots are placed after a note the second dot adds half the value of the first dot. A double dotted whole note would therefore be equal to a whole note, a half note and a quarter note.	11

First exercise in whole, half and quarter notes.
Care should be taken in the time, giving each note
the proper number of counts, always counting aloud.
Always be careful about the fingering; it is essential
to good piano playing.
Play each exercise several times on the Player, and then
practice by hand, from the notes, until you can play it
as well.

Count 1 2 3 1 2 3

Notes connected by one line A B C E E

We have present the first piece in $\frac{3}{4}$ or waltz time, and you will notice it differs from $\frac{4}{4}$ time, because there are but three counts to each measure. Pay strict attention to the time as played by the player roll and count time aloud, three counts to each measure. The half notes having two counts and the quarter notes one count. Notes connected thus (F) (F) should be played at the same instant, and by watching the piano keys when using the player you will see how the notes are struck.

INVENTOR.
Irving M. Smith.
BY A. B. Bowman
ATTORNEY

UNITED STATES PATENT OFFICE.

IRVING M. SMITH, OF SAN DIEGO, CALIFORNIA, ASSIGNOR TO THE Q R S MUSIC COMPANY.

MEANS OF TEACHING PIANO PLAYING.

Application filed June 5, 1919. Serial No. 301,958.

To all whom it may concern:

Be it known that I, IRVING M. SMITH, a citizen of the United States, residing at San Diego, in the county of San Diego and State 5 of California, have invented a certain new and useful Means of Teaching Piano Playing, of which the following is a specification.

My invention relates to a means and 10 method of teaching piano playing by the use of a player piano with a special roll provided with short music exercises with illustrative, descriptive and instructive subject matter properly positioned relatively to 15 said music and the objects of my invention are: First, to provide a new and novel means and method of teaching pupils piano playing; Second, to provide a music roll adapted for player pianos with music exercises to be played on the player piano and 20 with illustrative, descriptive and instructive subject matter on the face of the roll and in close proximity to the music being played so that the pupil may watch and 25 finger the player piano and thereby receive exact illustrative operation and fingering habit of the piano on the music played; Third, to provide a music roll of this class with exercises in different progressive stages 30 for the pupil to take up as he progresses; Fourth, to provide a means and method of this class whereby a student may learn all the fundamental principles of music by illustration, instruction and operation of a 35 player piano in their combined relation and without personal instruction; Fifth, to provide a new and novelly constructed player piano music roll; Sixth, to provide a means and method for teaching piano playing by 40 means of a player piano and special roll in which one or more rolls of ordinary length contains all the necessary instructions, music, illustration, demonstration and operation necessary to a complete and practical 45 understanding of piano playing and Seventh, to provide a means and method of this class which is very simple and economical of construction, durable, easy to operate and efficient in its action.

With these and other objects in view as 50 will appear hereinafter, my invention consists of certain novel features of construction, combination and arrangement of parts and portions and the certain steps taken as

will be hereinafter described in detail and 55 particularly set forth in the appended claims, reference being had to the accompanying drawings and to the characters of reference thereon which form a part of this application, in which:

Figure 1 is a plan and diagrammatical view of a fragmentary portion of a music roll illustrating the first or elementary lessons and exercises; Fig. 2 is a similar view 60 illustrating several of the more difficult exercises; Fig. 3 is a similar view illustrating the third and fourth and more advanced exercises; Fig. 4 is a similar view illustrating the fifth and sixth and more advanced exercises; Fig. 5 is a similar view illustrating 65 the seventh and eighth and more advanced exercises; Fig. 6 is a similar view illustrating the ninth and tenth and more advanced exercises; Fig. 7 is a similar view illustrating the eleventh and more advanced exercise and Fig. 8 is a similar view illustrating 70 the twelfth and more advanced exercise.

The music roll is of the conventional width for use on the player piano and is of the conventional shape and form generally 75 provided with the usual music perforations. It is provided on its face near the beginning with a staff with a complete scale of half notes with letters designating each 80 particular note of the scale and its position on the staff, the upper portion of the staff is shown in treble clef and the lower portion in base clef all designated by the numeral 85 1. 2 represents a blank staff. 3 represents a staff with numerals indicating the lines of 90 the staff. 4 represents a staff with numerals indicating the spaces between the lines. 5 represents the staff in the base clef with letters positioned on the lines and in the spaces 95 between the lines indicating the positions of the notes on the staff. 6 is a similar staff in treble or G clef. 7 represents a staff in the base or F clef with the ledger lines with letters indicating the position of the notes on the ledger lines. 8 represents a similar staff 100 in the treble or G clef. 9 represents the right and left hand positions, with the fingers properly marked and 10 represents the perforation exercise in the music roll for use on the player piano and it will be noted 105 that each perforation is provided with a number and letter indicating the finger and the scale in which it is played and that this

exercise marked number 10 is a scale as illustrated on the double staff 1 as hereinbefore described. It will also be noted that in connection with the perforations 10 there is provided descriptive matter for the pupil to read while the exercise is being played on the player piano as well as watching the scale and notes on the staff 1.

In Fig. 2 of the drawings is shown a continuation of the music roll from Fig. 1. There is provided a staff 11 with varying musical characters thereon with descriptive matter describing each character in a concise manner more particularly relating to time.

It will be here noted that 12 on the various views indicates the tempo in which the various exercises are to be played. The exercise perforations 13, 14, 15, 16, 17 and 18 show the exercises as illustrated in the scale 11 to be played on the player piano and on the one side of said perforations is the staff showing the position of the notes relatively to the staff and upon the other side is descriptive matter setting forth the kind of notes such as whole notes, half notes, quarter notes, etc. The descriptive matter is to be followed while the exercises 13 to 18 inclusive are being played on the player piano. In Fig. 3 is shown a continuation of the music roll from Fig. 2 showing the more advanced exercises 3 and 4 and illustrating together with the music a staff 19 with the notes in position with their reference letters in connection therewith and with numerals indicating the finger for both left and right hand, also the perforations 20 in said roll with corresponding letters and numerals indicating the finger markings shown in exercise 3 while exercise 4 shows a more advanced exercise with letters indicating the notes and numerals indicating the fingers with perforations 21 for the player piano corresponding with the music shown on the staff 22. Fig. 4 is a continuation of the roll from that of Fig. 3 and illustrates an exercise for both hands together in half notes with perforations 22 on the roll for playing on the player piano while the music is being watched by the pupil and exercise 6 on the same figure is a more advanced exercise. In the Figs. 5, 6, 7 and 8 which are continuations of the roll, there are provided more advanced exercises gradually eliminating the lettering and finger markings in connection with the perforations and music as the exercises become more advanced.

It will be noted that the roll may be carried on to very advanced stages if desired or several rolls may be used, each exercise with the perforations for playing on a player piano being provided with the music and descriptive, illustrative and instructive matter in connection therewith for the pupil to watch as it is being played on the piano so that the pupil acquires a knowledge and

practice of practically perfect time and position as the pupil may count aloud as the music is played on the player piano and watch the keys of the player piano in connection with the music as the music is played. That the pupil may place his fingers on keys of the player piano as the music is being played and watch the finger markings beside the perforations as shown in Fig. 3, exercise 3, thus acquiring the habit of proper fingering.

It will be also noted that in Fig. 8, exercise 12 there is provided music to be played in three-four time with descriptive matter thus providing the descriptive illustrative matter together with the perforations for the music on the player piano. All previous counts being four counts for each measure, while in this instance there are only three counts for each measure.

Though I have shown and described a particular means and method of teaching piano playing I do not wish to be limited to this particular means and method as illustrated and described but desire to include in the purview of my invention the means and method substantially as set forth in the appended claims.

Having thus described my invention what I claim as new and desire to secure by Letters Patent, is:

1. A music instruction strip comprising, a movable sheet bearing visual textual precept, and an immediately following perforation adapted to result in an actuation of a musical instrument in audible illustration of the precept, combined substantially as set forth.

2. A music instruction strip comprising, a movable sheet bearing a visual textual precept, a pictorial illustration following the precept, and a contiguous perforation adapted to result in an actuation of a musical instrument in audible illustration of the precept and illustration, combined substantially as set forth.

3. A music roll for player pianos provided with a plurality of sets of music perforations and note and finger markings at the sides of and in close proximity with each set of perforations.

4. A music roll for player pianos provided with a plurality of sets of music perforations, note and finger markings in close proximity with each set of perforations and music on the face of the roll in close proximity thereto adapted to be seen as the roll is being played.

5. A music roll for player pianos provided with a plurality of sets of music perforations, note and finger markings in close proximity with each set of perforations, music on the face of the roll so positioned that it is adapted to be seen as the roll is being played and descriptive, instructive and illustrative matter on the face of the

roll at the side of, and adjacent the perforations adapted to be seen while the roll is being played.

6. A music roll for player pianos provided with a plurality of music perforations, note and finger markings at the sides of and in close proximity with each perforation, music on the face of the roll at the side of and adapted to be seen as the roll is being played, 10 descriptive, instructive and illustrative matter on the face of the roll at the side of and adapted to be seen while the roll is being played and more difficult exercises on the same roll following immediately thereafter 15 with illustrative, instructive and descriptive matter relating thereto in close proximity thereto.

7. In a music roll for player pianos, the combination of the ordinary music roll with 20 perforations and instructive, illustrative and descriptive matter mounted on the face of the roll at the side of and in close proximity with said perforations, whereby the same may be readily observed and read while the 25 music is being played.

8. A device, for use with an automatic musical instrument, provided with means for selectively causing the sounding of the notes of a selection, and provided also with means 30 for indicating to a pupil how the selection is to be played manually.

9. A device, for use with an automatic musical instrument, provided with means for causing the sounding of the notes of a selection, and provided also with means for indicating to a pupil how the hand is to be used in manually causing the corresponding 35 notes to be sounded.

10. A device, for use with an automatic 40 key-board musical instrument, provided with means for selectively causing the sounding of the notes of a selection, and provided also with means for indicating to a pupil the keys which should be struck in 45 playing the selection manually.

11. A device, for use with an automatic key-board musical instrument, provided with means for selectively causing the sounding of the notes of a selection, and provided also with means for indicating to a pupil what fingers are to be used in manually playing the selection. 50

12. A device, for use with an automatic musical instrument, provided with means for selectively causing the sounding of the notes of a selection, and provided also with means for indicating to a pupil what keys are to be struck, and what fingers are to be used, in manually playing the selection. 55

13. A device, for use with an automatic musical instrument, provided with means for selectively causing the sounding of the notes of a selection, and provided also with means for indicating to a pupil how the selection is to be played manually, and provided also 60 with the writer score of the musical selection. 65

14. A music roll comprising a strip with perforations to control the production of notes, the strip having insignia adjacent to 70 a perforation to indicate the note sounded by said perforation, and also insignia to indicate the finger to be used in manual playing of the identified note.

15. A music roll comprising a strip with 75 perforations to produce a melody and also associated notes, and having insignia adjacent each perforation to indicate the finger and hand to be used in manual playing of the notes, and having an indicator for identifying 80 the melody notes.

16. A music roll for player pianos provided with a plurality of music perforations and note and finger markings in close proximity with each perforation. 85

In testimony whereof, I have hereunto set my hand at San Diego, California this 31 day of May 1919.

IRVING M. SMITH.
